Application May 9, 1946, Serial No. 668,442

11 Claims. (Cl. 250—27)

1

This invention relates to trigger circuits of the multivibrator type, and has for its principal object the provision of an improved trigger circuit which operates at speeds much higher than those heretofore realized in connection with circuits of this type.

Such trigger circuits in the past have included a pair of triode elements each of which has its anode coupled to the control grid of the other through a capacitor which may be shunted by a resistor. Operating potential is applied through separate resistors to the anodes of the triode elements, bias potential is applied through separate resistors to their control grids, and their cathodes may be grounded.

With these connections, only one of the triode elements conducts current at a time, and current conductivity is transferred from one to the other in response (1) to the application of a negative pulse to the grid of a triode element which is conducting, (2) to the application of a positive pulse to the grid of a triode element which is not conducting, or (3) to the application of a negative pulse to the common anode terminal of the two triode elements in the case where a resistor common to both anodes is connected between the individual anode resistors and the +B lead.

The time required for this transfer of current conductivity from one of the triode elements to the other is dependent on the rate at which energy is stored in the grid capacitor of the conducting triode when a control pulse is applied for transferring current conductivity from one of the triode elements to the other. It has been found that this time cannot be decreased below about one microsecond. Where higher speeds of the transfer of current conductivity are desired, it is evidently necessary to provide a path of lower impedance for charging the grid capacitor of the conducting triode element.

In accordance with the present invention, this is accomplished by providing an electron discharge path through which the energy is stored in the grid capacitor more quickly. This serves to speed up the action of the trigger circuit to such an extent that current conductivity is transferred from one of the triode elements to the other in a time which is of the order of one tenth of a microsecond.

The electron discharge path through which charging of the grid capacitor is accelerated may be in the form of a triode (1) connected in shunt to the individual anode resistor of the trigger circuit so that the grid capacitor is charged through the triode and the anode resistor in par-

2

allel, or (2) connected between the anodes of the trigger circuit so that the grid capacitor is charged through the individual anode resistors in parallel and to some extent perhaps through the triode element of the trigger circuit to which current conduction is being transferred. These low impedance paths for charging the grid capacitors greatly speed up the response of the trigger circuit to the driving pulse by which current conduction is transferred from one to another of the triode elements.

The driving pulse is applied to the control grids of the triodes which are normally biased to cut off and function to charge the grid capacitors.

15 The invention is applicable to many different types of apparatus such as counters where a plurality of trigger circuits are connected in cascade with one another. It is illustrated herein as applied to a high speed electronic switching device.

20 One important use of such electronic switching devices is the control of the application of timing pulses to an electronic counter which indicates the number of constant frequency pulses applied between opening and closing of the switch. The 25 switch of the present invention is useful for this purpose and for numerous other purposes involving very high speed switching operations which are to be executed in a time interval of the order of one-tenth microsecond or less.

30 The principal object of the invention is the provision of an improved trigger circuit and method of operation whereby the operating time of such a circuit is greatly reduced. Other important objects are the provision of a high speed switching device, the provision of a trigger circuit affording a low impedance path for the charging of its grid capacitors, the provision of an improved high speed coupling between trigger circuits, and the provision of an improved means

35 for applying to a trigger circuit the driving pulses by which current conduction is shifted to and fro between its mutually exclusive electron discharge elements.

40 The invention will be better understood from the following description considered in connection with the accompanying drawings and its scope is indicated by the appended claims.

45 Referring to the drawings:

Fig. 1 is a wiring diagram of a trigger circuit wherein the triodes for charging the grid capacitors have a constant bias applied to their control grids and are connected in shunt to the individual anode resistors, the driving pulses being applied only to the control grids of such triodes.

50 Fig. 2 illustrates a modification which differs

from that of Fig. 1 in that the control triodes have a variable bias derived from the trigger circuit and the driving pulses are applied also to the control grids of the trigger circuit.

Fig. 3 is a wiring diagram of a trigger circuit wherein the triodes for charging the grid capacitors of the trigger circuit are connected between the anodes of this circuit, and,

Fig. 4 is a wiring diagram of a high speed switching device including two trigger circuits 10 which (1) each have their anodes interconnected through a triode for discharging one of their grid capacitors and (2) are coupled together through a triode which greatly accelerates the transmission of pulses between the two trigger circuits.

The trigger circuit of Fig. 1 includes a pair of triodes 10 and 11. The triode 10 includes an anode 12 which is connected to the +B lead through a resistor 13, a cathode 14 which is grounded, and a control grid 15 which is coupled through a capacitor 16 to the anode 17 of the triode 11. The capacitor 16 is shunted by a resistor 18 and a constant bias potential is applied to the grid 15 through a resistor 19. The triode 11 includes the anode 17 which is connected to the +B lead through a resistor 20, a cathode 21 which is grounded, and a control grid 22 which is coupled through a capacitor 23 to the anode 12. The capacitor 23 is shunted by a resistor 24 and bias potential is applied to the grid 22 through a resistor 25.

Up to this point the connections of the trigger circuit are old and well known. It has been customary heretofore to effect the transfer of current conduction from the triode 10 to the triode 11 and vice versa by means of a driving pulse applied directly to the grid 15 or the grid 22.

In accordance with the present invention, such transfer of current conduction is effected by means of a triode 26 connected in shunt to the resistor 13 and a triode 27 connected in shunt to the resistor 20. To this end, the triode 26 has its anode 28 connected to one terminal of the resistor 13, its cathode 29 connected to the other terminal of the resistor 13 and its control grid 30 connected through a resistor 31 and a capacitor 32' to a source of driving pulses. The triode 26 is normally biased to cut off by a potential derived from a resistor 33 and is made conductive by a positive driving pulse applied through the capacitor 32' to the grid 30. The triode 27 has its anode 35 connected to one terminal of the resistor 20, its cathode 36 connected to the other terminal of this resistor and its control grid 37 connected through a capacitor 32 to the source of driving pulses. The triode 27 is normally biased to cut off by a potential applied through the resistors 33 and 39 and is made conductive by a positive pulse applied through the capacitor 32. A reset switch 41 may be opened and closed to establish a standby condition with current conduction in the triode 10 as indicated by the arrow.

With current conduction in the triode 10 as indicated, the potential of the anode 12 is more negative due to the voltage drop of the resistor 13 and the potential of the anode 17 is at substantially +B voltage due to the relatively small current in the resistor 20. Under these conditions, the application of a positive driving pulse to the grid 37 cannot start current through the triode 27 for the reason that its anode and cathode are at substantially the same voltage. The application of a positive driving pulse to the grid 30 however, makes the triode 26 conductive so that (1) a

more positive voltage is applied through the resistor 24 to the grid 22, (2) the capacitor 23 is quickly charged, and (3) current conduction is transferred from the triode 10 to the triode 11. In the same way, current is transferred from the triode 11 to the triode 10. It is evident that the trigger circuit of Fig. 1 may be coupled through a capacitor 42 or a triode to a second trigger circuit for transferring a driving pulse to such second trigger circuit when current conduction is transferred from the triode 11 to the triode 10.

The modification of Fig. 2 is like that of Fig. 1 for the most part but differs therefrom in that the driving pulses also are applied (1) through a resistor 43 and an adjustable part of the resistor 24 to the grid 22 of the triode 11, and (2) through a resistor 44 and an adjustable part of the resistor 18 to the grid 15 of the triode 10. The operation of the modification of Fig. 2 is like that of the modification of Fig. 1 with the exception that the grids of the tubes 26 and 27 of Fig. 2 have their bias potentials changed while the trigger circuit is operating. Thus with current conduction in the tube 10 as indicated by the arrow, the grid 37 is more negative than the grid 30 which provides the condition required for charging the capacitor 23 and transferring conduction to the tube 11.

In the modification of Fig. 3, the triodes 26 and 27 for charging the grid capacitors 23 and 16 are connected between the anodes 12 and 17 of the trigger circuits. As in the previous modifications, the triodes 26 and 27 are normally biased to cut off and driving pulses may be applied to the grids 30 and 37 through a common lead or through separate leads 45 and 46. Thus the application of a positive driving pulse to the lead 45 makes the triode 26 conductive so that current is drawn through the resistor 20, the capacitor 23 is quickly charged through the triode 26 and the resistors 13 and 20, and current conduction is transferred from the triode 10 to the triode 11. The application of a positive pulse to the lead 46 is effective in the same way to transfer current conduction from the triode 11 to the triode 10.

Through the capacitor 42, the trigger circuit of Fig. 3 (as well as those of Figs. 1 and 2) may be coupled to a second trigger circuit, such coupling being made to the second circuit at the grid of the triode which does not conduct current in the standby condition of the trigger circuit.

The switch device of Fig. 4 includes two trigger circuits 47 and 48 which are coupled together through a triode 49 and are similar to the trigger circuit of Fig. 3 in several respects. Thus the trigger circuit 47 has a triode 58 connected between its anodes 51 and 52, and the trigger circuit 48 has a triode 53 connected between its anodes 54 and 55. The trigger circuit connections are otherwise similar to those of the trigger circuits of Figs. 1 to 3.

Thus the trigger circuit 47 has its cathode 56 grounded, has bias potential applied from a lead 57 through a resistor 58 to its right hand grid 59, has bias potential applied from a lead 60 through a resistor 51 to its left hand grid 62, has its anodes 51 and 52 connected to the +B terminal through resistors 63 and 64 respectively, has its anode 51 coupled to its grid 59 through a capacitor 65 which is shunted by a resistor 66 and has its anode 52 coupled to its grid 62 through a capacitor 67 which is shunted by a resistor 68.

Similarly the trigger circuit 48 has bias potential applied to its grids 69 and 70 through re-

sistors 71 and 72, has its cathode 73 grounded, has its anodes 54 and 55 connected to the +B lead through resistors 74 and 75, has its anode 54 coupled to its grid 70 through a capacitor 76 which is shunted by a resistor 77, and has its anode 55 coupled to its grid 69 through a capacitor 78 which is shunted by a resistor 79.

A reset switch 41 is opened and closed to establish a standby condition with current conduction in the left hand triodes of the trigger circuits 47 and 48 as indicated by the arrows placed adjacent the anode resistors 63 and 74.

When the switching device including the trigger circuits 47 and 48 is open, constant frequency oscillations (indicated at 80) applied through a lead 81 to the grid 82 of a triode 83 are delivered at an output lead 84. When the switching device is closed, delivery of the constant frequency pulses at the output lead 84 is interrupted.

The switching device is opened in response to a positive pulse applied from a lead 85 through a capacitor 86 to the grid 87 of the triode 49 which (1) is normally biased to cut off by the voltages of the resistors 88 and 89 (2) has its cathode 90 connected to the anode 54 of the trigger circuit 48, and (3) functions to couple the trigger circuit 48 to the trigger circuit 47 so that the positive driving pulse applied to the grid 87 makes the grid 62 more negative thereby transferring current conduction from the anode 51 to the anode 52 of the trigger circuit 47.

When current conduction is transferred from the anode 51 to the anode 52, the anode 51 becomes more positive and the anode 52 more negative. The more negative potential of the anode 52 functions to light the run indicator R and to make the cathode 92 of the triode 50 more negative. The more positive potential of the anode 51 functions (1) to apply a more positive potential to the grid 96 of the cathode follower 97 thereby causing it to draw more current through the resistors 98 and 99 and biasing on the tube 83 so that constant frequency pulses (indicated at 100) are delivered at the output lead 84, (2) to make the anode 91 of the triode 50 more positive, (3) to apply through a capacitor 101 to the grid 102 of the triode 53 a more positive voltage which causes the triode 53 to draw more current through the resistor 75 and to produce at the grid 69 a more negative voltage so that current conduction is transferred from the anode 54 to the anode 55.

When this occurs, there is applied from the anode 54 through a lead 103 and a resistor 104 to the grid 95 of the triode 50 a more positive voltage whereby the triode 50 is biased just below cut off.

Under these conditions, the application of a positive stop pulse to the lead 93 makes the triode 50 conductive so that it draws more current through the resistor 63 and produces at the grid 59 a more negative voltage whereby current conduction is transferred from the anode 52 to the anode 51. Transfer of current conduction from the anode 52 to the anode 51 (1) turns off the run indicator R and turns on the stop indicator S, and (2) biases off the triodes 97 and 83 so that the delivery of the constant frequency pulses from the output lead 84 is interrupted.

The switching device is now in a lock out condition so that it is insensitive to driving pulses applied over the leads 85 and 93. It may be returned to its standby condition by opening and closing the reset switch 41 which functions to es-

tablish current conduction in the anodes 51 and 54 of the trigger circuits 47 and 48.

By means of the push buttons 105 and 106, the trigger circuit 47 may be put into a run or stop condition independently of the delivery of driving pulses over the leads 85 and 93. Thus when the push button 106 is closed, more current is drawn through a resistor 107 and the resistor 68 making the grid 62 more negative. Likewise closing of the push button 105 results in more current through the resistors 107 and 66 and a more negative potential at the grid 59.

The triodes 50 and 53, like the corresponding triodes of Figs. 1 to 3, function to speed up the action of the trigger circuits 47 and 48 of Fig. 4. Thus when current conduction is transferred from the anode 51 to the anode 52 of the trigger circuit 47, the grid capacitor 65 is rapidly charged through the low impedance path afforded by the triode 50 and, when current conduction is transferred from the anode 54 to the anode 55 of the trigger circuit 48, the grid capacitor 76 is rapidly charged through the low impedance path of the triode 53. The triode 49, of course, affords a quick acting coupling between the trigger circuits 48 and 47 so that the negative voltage then existing at the anode 54 is applied to the grid 62 substantially instantaneously in response to the driving pulse delivered over the lead 85. As previously explained, the run and stop pulses may be applied to the grids of the tubes 50 and 49 over a single lead instead of over the separate leads 85 and 93.

What the invention provides is a trigger circuit which acts at a speed much higher than the speeds heretofore realized with trigger circuits of similar types. While the improved trigger circuit has been illustrated as applied to a high speed switching device, obviously it is applicable to electronic counters and to other types of devices involving the use of one or more trigger circuits.

I claim as my invention:

1. The combination of a trigger circuit including a pair of triodes each having operating potential applied to its anode through a separate resistor and each having its grid coupled to the anode of the other triode through a separate capacitor, and means connected between said anodes for providing a low impedance charge path for one of said capacitors only when current conduction is transferred to the triode having said one capacitor connected in its grid circuit.

2. The combination of a trigger circuit including a pair of triodes each having operating potential applied to its anode through a separate resistor and each having its grid coupled to the anode of the other triode through a separate capacitor so that current conduction is in one or the other of said triodes, and a control triode having its cathode connected to the anode of the triode of said trigger circuit which is conducting and its anode connected to the anode of the triode of said trigger circuit which is not conducting.

3. The combination of a trigger circuit including a pair of triodes each having operating potential applied to its anode through a separate resistor and each having its grid coupled to the anode of the other triode through a separate capacitor so that current conduction is in one or the other of said triodes, a control triode having its cathode connected to the anode of the triode of said trigger circuit which is conducting and its anode connected to the anode of the triode of said trigger circuit which is not conducting, and means for applying to the grid of said control

triode a driving pulse whereby current conduction is transferred from one to another triode of said trigger circuit.

4. The combination of a pair of trigger circuits of the type wherein a pair of triodes have operating potential applied to their anodes through separate resistors and each triode has its grid coupled through a capacitor to the anode of the other triode of the pair so that current conduction is in one or the other triode of the pair, means for establishing current conduction in a predetermined triode of each pair, a coupling triode having its cathode connected to the anode of the conducting triode of one of said trigger circuits and its anode connected to the anode of the non-conducting triode of the other of said trigger circuits, and means for applying to the grid of said coupling triode a driving pulse whereby current conduction is transferred from one triode to the other triode of said other trigger circuit.

5. The combination of a pair of trigger circuits of the type wherein a pair of triodes have operating potential applied to their anodes through separate resistors and each triode has its grid coupled through a capacitor to the anode of the other triode of the pair so that current conduction is in one or the other triode of the pair, means for establishing current conduction in a predetermined triode of each pair, a coupling triode having its cathode connected to the anode of the conducting triode of one of said trigger circuits and its anode connected to the anode of the non-conducting triode of the other of said trigger circuits, means for applying to the grid of said coupling triode a driving pulse whereby current conduction is transferred from one triode to the other triode of said other trigger circuit, an output lead, and means responsive to said transfer of current conduction for initiating the delivery of pulses to said output lead.

6. The combination of a pair of trigger circuits of the type wherein a pair of triodes have operating potential applied to their anodes through separate resistors and each triode has its grid coupled through a capacitor to the anode of the other triode of the pair so that current conduction is in one or the other triode of the pair, means for establishing current conduction in a predetermined triode of each pair, a coupling triode having its cathode connected to the anode of the conducting triode of one of said trigger circuits and its anode connected to the anode of the non-conducting triode of the other of said trigger circuits, means for applying to the grid of said coupling triode a driving pulse whereby current conduction is transferred from one triode to the other triode of said other trigger circuit, and means responsive to said transfer of current conduction in said other trigger circuit for transferring current conduction in said one trigger circuit.

7. The combination of a pair of trigger circuits of the type wherein a pair of triodes have operating potential applied to their anodes through separate resistors and each triode has its grid coupled through a capacitor to the anode of the other triode of the pair so that current conduction is in one or the other triode of the pair, means for establishing current conduction in a predetermined triode of each pair, a coupling triode having its cathode connected to the anode of the conducting triode of one of said trigger circuits and its anode connected to the anode of the non-conducting triode of the other

of said trigger circuits, a stop triode having its anode and cathode respectively connected to the anode of the conducting triode and the anode of the non-conducting triode of said other trigger circuit and its grid coupled to the anode of the conducting triode of said one trigger circuit, means for applying to the grid of said coupling triode a driving pulse whereby current conduction is transferred from one triode to the other triode of said other trigger circuit, means responsive to said transfer of current conduction in said other trigger circuit for transferring current conduction in said one trigger circuit, said stop triode having its cathode anode potential reversed by said transfer of current conduction in said other trigger circuit and its grid potential made more positive by said transfer of current conduction in said one trigger circuit, means for delivering pulses to an output lead, a cathode follower tube connected to control said pulse delivering means and to be responsive to the current conductive condition of said stop triode, and means for applying to the grid of said stop triode a driving pulse whereby the delivery of said pulses to said output lead is stopped and current conduction is transferred in said other trigger circuit.

8. The combination of a pair of trigger circuits of the type wherein a pair of triodes have operating potential applied to their anodes through separate resistors and each triode has its grid coupled through a capacitor to the anode of the other triode of the pair so that current conduction is in one or the other triode of the pair, means for establishing current conduction in a predetermined triode of each pair, a coupling triode having its cathode connected to the anode of the conducting triode of one of said trigger circuits and its anode connected to the anode of the non-conducting triode of the other of said trigger circuits, means for applying to the grid of said coupling triode a driving pulse whereby current conduction is transferred from one triode to the other triode of said other trigger circuit, a control triode having its cathode connected to the conducting anode of said one trigger circuit and its anode connected to the other anode of said one trigger circuit, and means connecting the grid of said control triode to an anode of the other trigger circuit so that said transfer of current conduction in said other trigger circuit produces transfer of current conduction in said one trigger circuit.

9. The combination of a trigger circuit including a first pair of electron discharge tubes each having anode, cathode and grid electrodes, each having its anode connected to a source of operating potential through a separate resistor and each having its grid electrode coupled to the anode of the other electron discharge tube through a separate capacitor, means to maintain said trigger circuit stable with conduction in one or the other of said first pair of tubes, and a second pair of electron discharge tubes having anode, cathode and grid electrodes each of which has its cathode connected to the anode of a separate one of said first pair of tubes and its anode coupled to said source of operating potential, means to apply a bias to the grids of said second pair of tubes to render said tubes normally non-conducting, and means to apply a driving pulse to a grid of said second pair of tubes to render conductive the one of said second pair of tubes the cathode of which is connected to the anode of a conducting one of said first pair of tubes to

charge the condenser connecting the anode of said one of said first pair of tubes to the grid of the other of said first pair of tubes through said one of said second pair of tubes and to transfer conduction from said one to said other of said first pair of tubes.

10. The combination recited in claim 9 wherein each of the anodes of said second pair of tubes is respectively connected to the end of each of said separate resistors nearest said source of operating potential whereby each of said second tubes is connected across one of said separate resistors through which operating potential is applied to the anodes of said first pair of tubes.

11. The combination recited in claim 9 wherein said means to apply a bias to the grids of said second pair of tubes comprises a pair of adjustable resistors connected across each of said capacitors whereby each of said resistors is in series with the cathode of one of said second tubes and means to connect an adjustable portion of each of said adjustable resistors to the

respective grid of the one of said second tubes having said other adjustable resistor in series with its cathode.
